UNITED STATES PATENT OFFICE.

HORACE FENTON, OF WETHERSFIELD, CONNECTICUT.

LINE-FASTENER.

SPECIFICATION forming part of Letters Patent No. 225,923, dated March 30, 1880.

Application filed February 16, 1880.

To all whom it may concern:

Be it known that I, HORACE FENTON, of Wethersfield, in the county of Hartford and State of Connecticut, have invented certain new and useful Improvements pertaining to a Hitch-Block for Ropes, &c., of which the following is a specification, reference being had to the accompanying drawings, where—

Figure 1 is a perspective, showing top and one side of the hitch-block. Fig. 2 is a perspective, showing the bottom and one side of the hitch-block. Fig. 3 shows a section on the line xx of Fig. 2.

The letter a denotes the containing-case, preferably made of metal and cast in one piece. The letter b denotes the hinged lid or cover thereof, and c the hinged clamp to hold the lid shut. The case is provided with the screw d , whereby the device may be attached to a post or the like. Within the case is a cogged roll or roll-gear, e , traveling on a cogged ratch, f . Preferably, but not necessarily, the opposite side of the case bears another cogged ratch, g . The letter h denotes the rope, cord, or line. The ratch f is inclined, so that as the

cogged roll falls back from the mouth i the rope is free to run; but when the cogged roll approaches the mouth i it catches the rope between itself and the opposite side of the case and holds it from running out.

It will be readily understood that a pull on the rope in the direction denoted by the arrow will loosen the rope so that it will run, and that a pull in the opposite direction will tighten it so that it will not run.

I have devised a modification of this invention to be applied to a pulley-block, in which the pulley-block takes the place of the cogged ratch g . The details of that modification I reserve as subject-matter for other Letters Patent; but the general operating principle is the same as in the device herein described.

I claim as my invention—

In combination, the case a , provided with the lid b , the screw d , and ratches f g , and the cogged roll e , substantially as described.

HORACE FENTON.
